UNITED STATES PATENT OFFICE.

ALFRED JOHNSON, ARTHUR C. SWANSON, AND ALFRED H. UTTERBERG, OF CHICAGO,
ILLINOIS.

PNEUMATIC ACTION.

1,274,055.

Specification of Letters Patent. Patented July 30, 1918.

Application filed October 23, 1916. Serial No. 127,066.

To all whom it may concern:

Be it known that we, ALFRED JOHNSON and ARTHUR C. SWANSON, both citizens of the United States, and ALFRED H. UTTERBERG, a subject of the King of Sweden, residents of Chicago, in the county of Cook and State of Illinois, have invented certain new and useful Improvements in Pneumatic Actions, of which the following is a specification.

Our invention relates to self-playing musical instruments, and particularly to improve pneumatic action therefor.

The object of our invention is to simplify and improve the construction and arrangement of the valve mechanism for controlling the operation of the action pneumatics to reduce the cost of manufacture and to make inspection and repairs easier.

On the accompanying drawings a structure is shown embodying the features of our invention. In these drawings

Figure 1 is a plan view of a pneumatic action unit,

Fig. 2 is a sectional view on plane 2—2, Fig. 1,

Fig. 3 is a plan view with the top cover removed and the valve seat supporting flexible member swung back to reveal the construction in the diaphragm chamber,

Fig. 4 is a side elevational view of an improved form of valve, and

Fig. 5 is an under side view thereof.

The unit shown comprises the rectangular body block 10 having the extension 11 integral therewith. A plate 12 is hinged at its rear end to the bottom of the body at one end thereof and extends below the body and the extension 11, flexible fabric 13 being secured to the plate 12 and to the body 10 and its extension 11 to form the action bellows. The block 10 is bored vertically to leave the annular slot 14 around the platform 15 whose top is below the top of the block to leave the space 16 above the diaphragm 17 which is secured at its periphery to the rim of the platform, the platform being hollowed out to provide the space 18 below the diaphragm and the central pocket 19. Surrounding the upper end of the space 16 is the depressed annular seat 20 for a metal

valve disk 21, a sealing washer 22 being preferably applied between the disk and seat. The disk has the central opening 23 forming a passageway between the space 16 and the valve chamber 24 in the cover 25 secured to the block 10 by screws 26, a passageway 27 in the cover connecting the valve chamber with the passageway 28 leading to the interior of the action bellows. Above the valve chamber 24 the cover 25 has the atmosphere port 29.

The ports 23 and 29 are controlled by a valve *v* whose movement is controlled by the diaphragm 17 and atmospheric pressure. The construction of the valve forms an important feature of our invention. It comprises a disk 30 preferably of wood which has a plurality of guide legs 31 extending downwardly therefrom, these legs extending through the port 23 to guide the valve as it is moved upwardly and downwardly during operation of the action. These guide legs can be of sufficient length to be engaged directly by the diaphragm when the diaphragm is forced upwardly, but preferably an adjustable abutment is provided for the diaphragm. As shown, a screw 32 threads centrally through the disk 30 and terminates at its lower end in a head 33 to be engaged by the diaphragm, the upper end 34 being flattened to receive a tool for turning the screw to adjust its head with reference to the diaphragm, the diaphragm having preferably a stiff reinforcing abutment disk 35 secured to its upper face. The top of the disk 30 is faced by a layer 36 preferably of leather for insuring air-tight engagement of the valve around the air port 29 when the valve is up.

Between the cover 25 and the body 10 we interpose a sheet 37 of soft flexible material preferably leather, this sheet extending over the metal valve disk 21 and has the central opening in register with the opening 23 of the disk. The sheet 37 forms a sealing seat for the valve *v* around the opening or port 23, and the sheet is also compressed between the body 10 and cover 25 to form a seal between the chamber 16 and the valve chamber 24 when the valve is down. Preferably also the metal valve disk 21 is supported on the flexible sheet 37 by being glued thereto so

that when the cover 25 is removed the sheet with the valve seat thereon can be readily removed to give access to the diaphragm. To insure proper receiving of the valve seat 5 disk the sheet is glued to the top of the body at the outer end thereof, as indicated at 38. Then when the cover 25 is removed and the valve *v* withdrawn, the sheet can be swung back, as indicated in Fig. 3, to expose the 10 upper diaphragm chamber and the diaphragm.

Extending through the block 10 from the central pocket 19 below the diaphragm is a pipe 39 which in practice extends into one 15 of the passageways in the vacuum chest to be connected with one of the openings in the tracker board of the instrument. Passageways 40 through the block 10 extend from the upper diaphragm chamber 16 to 20 the block end to communicate with openings in the vacuum chest leading to the interior thereof. Normally the spaces above and below the diaphragm are under low pressure by being connected with the vacuum compartment 25 of the vacuum chest, atmospheric pressure then acting on the valve *v* through the port 29 to hold the valve open with the head of the screw 32 against the diaphragm. When the valve is down the interior of the 30 action pneumatic 13 is connected with atmosphere. As a music sheet travels over the tracker board and an opening thereof comes into registration with the tracker board opening, air under atmospheric pressure 35 will rush into space 19 below the diaphragm, the space above the diaphragm still being subject to low pressure, the result being that the diaphragm is thrown upwardly to raise the valve to close the atmosphere port 29 and to connect the action pneumatic 13 through the now open port 23 with the 40 vacuum space with the vacuum chest so that the plate 12 of the action pneumatic will be 45 swung upwardly. As shown, this plate has the usual extension 40 provided with a slot 42 for receiving the lower end of a striker rod. When the tracker board opening is again closed the pressure below the diaphragm is reduced to that above the diaphragm by virtue of the usual bleed passageway between the vacuum compartment of the vacuum chest and the atmospheric passageway to the space below the diaphragm, the valve being then shifted back to its lower position to close the port 23 and to reopen the atmosphere port 29 to the action pneumatic.

The structure of the valve *v* is extremely 60 simple, a block of wood being turned and cut to leave the disk 30 and the guide legs 31. By means of the screw 32 passing through the disk 30 the valve may be readily adjusted in relation to the diaphragm.

Only the top of the valve is faced with 65 leather, the leather sheet 37 forming a seat for the lower face of the valve. The section of the sheet above the chamber 16 is held in horizontal alinement by the seat disk 21 which is glued thereto and which is supported on the annular seat 20 surrounding the chamber 16. The sheet being hinged at one end to the block 10 by being glued thereto assures accurate seating of the disk 21 after it has been swung away from its 75 seat with the sheet.

We do not, of course, desire to be limited to the exact construction and arrangement shown, as changes are no doubt possible which would still come within the scope of 80 the invention.

We claim as follows:

1. In pneumatic action mechanism of the class described, the combination of a block having a diaphragm chamber, a diaphragm mounted in said chamber, an annular seat formed in said block above the diaphragm chamber, a metallic plate mounted on said seat and having a port above the diaphragm, a cover for the block having a valve chamber over said port and having an atmosphere passageway leading thereto, a sheet of flexible material clamped between said cover and block and having an opening in register with said port, and a valve in said valve chamber seating on said sheet and having guide legs extending through said port toward the diaphragm, said valve being actuated by the diaphragm to control said port and atmosphere inlet.

2. In pneumatic controlling mechanism of the class described, the combination of a block having a diaphragm chamber, a diaphragm mounted in said chamber, a cover on said block having a valve chamber therein and having an atmosphere inlet to said chamber, a sheet of flexible material clamped between the block and cover, a stiff plate secured to the under side of said sheet to fit over the diaphragm chamber, said sheet and plate having a port therethrough between the valve chamber and the diaphragm chamber, and a valve in said valve chamber having legs extending downwardly through said port to the diaphragm, said sheet forming a flexible sealing seat for the lower face of said valve.

3. In pneumatic controlling mechanism of the class described, the combination of a block having a diaphragm chamber, a diaphragm mounted in said chamber, a cover on said block having a valve chamber therein and having an atmosphere inlet to said chamber, a sheet of flexible material clamped between the block and cover, a stiff plate secured to the under side of said sheet to fit over the diaphragm chamber, said sheet and plate having a port therethrough between

the valve chamber and the diaphragm chamber, and a valve in said valve chamber having legs extending downwardly through said port to the diaphragm, said sheet forming a 5 flexible sealing seat for the lower face of said valve, said sheet being glued to the block along one end whereby it may be swung to carry said plate away from the

diaphragm chamber after removal of the cover from said block. 10

In witness whereof we hereunto subscribe our names this 19th day of October, A. D. 1916.

ALFRED JOHNSON.
ARTHUR C. SWANSON.
ALFRED H. UTTERBERG.
